[57] CLAIM

The ornamental design for a simulative toy sewing box
or similar article, as shown and described.

DESCRIPTION

FIG. 1 is a front elevational view of a simulative toy
sewing box or similar article showing my new design;
FIG. 2 is a right side elevational view thereof;
FIG. 3 is a rear elevational view thereof;
FIG. 4 is a left side elevational view thereof;
FIG. 5 is a bottom plan view thereof;
FIG. 6 is a top plan view thereof; and
FIG. 7 is a perspective view thereof with portions of the
design in alternate positions.

FIG. 1.**FIG. 2.****FIG. 3.****FIG. 4.****FIG. 5.****FIG. 6.****FIG. 7.**
